UNITED STATES PATENT OFFICE.

EDWIN A. MASTICK, OF CLEVELAND, OHIO.

ROOFING.

1,265,226.

Specification of Letters Patent.

Patented May 7, 1918.

Application filed December 26, 1916. Serial No. 138,775.

To all whom it may concern:

Be it known that I, EDWIN A. MASTICK, a citizen of the United States, residing at Cleveland, in the county of Cuyahoga and 5 State of Ohio, have invented certain new and useful Improvements in Roofing, of which the following is a specification.

My invention relates to roofing materials, and has for its object the provision of improved shingles which may be formed of 10 flexible material and curved longitudinally to represent Spanish tile, and the like.

A further object is the provision of shingles of the kind mentioned which will fit 15 closely together to make water-tight joints. Other objects will appear hereinafter.

An embodiment of my invention is shown in the accompanying drawing forming a part of this specification, and in which—

20 Figure 1 is an isometric fragmental view of a roofing construction embodying my invention.

Fig. 2 is an enlarged fragmental section taken as on line 2—2 in Fig. 1.

25 Fig. 3 is an enlarged perspective view of a shingle used in the construction; and

Fig. 4 is a perspective view of a portion of a strip used in the construction.

Referring more particularly to the drawing, I have shown a roofing construction 30 made up of a plurality of members, which for the purpose of this invention I term shingles. These shingles may be made of any suitable or desirable material. I find 35 that a suitable material may be formed with a paper or pulp backing having asphalt thereon with crushed slate pressed into the asphalt. Shingles made of this construction are of somewhat flexible nature. The ar- 40 rangement I have shown for securing them on the roof effectively holds them in their curved or arched conditions.

The roof shown comprises a sheeting 5 which may be of any preferred or conven- 45 tional construction. On this sheeting I preferably place a water-proof covering 6 of any desirable substance, such as roofing paper, or the like. This covering 6 may be dispensed with when the roof has consider- 50 able pitch and the shingles are sufficiently lapped to prevent moisture from passing up- 55 wardly between them. On the covering 6, or where the covering is not used, on the sheeting 5, I secure strips 7, which may be of wood, or any other desirable substance. The strips may be nailed to the sheeting, or

secured in any other desirable manner. The strips 7 are preferably spaced at distances so that an edge portion 8 of each shingle may be secured to one of the strips 7, and the upwardly curved or arched portion 9 of the shingle extend over the next adjacent strip 7, and rest on the next shingle. With this construction, the curved or arched portion 9 of the shingle will be maintained in 60 such curved or arched condition, since the portion 8 is nailed or otherwise secured to a strip 7, and the edge 10 of the shingle rests in a valley 11 of another shingle. This prevents the edge 10 from moving away from 65 the edge 8 and holds the shingle in its curved or arched condition. I have termed the hollow groove-like portion of the shingle between the parts 8 and 9 a valley for the purpose of this specification. 70

In order to make the shingles lie flat against one another in the roof so that substantially no air spaces will extend between the overlapped parts of the shingles, I cut away certain corners. The edge portion 8 80 of each shingle is cut away at its lower end, as at 12. The lower edge 13, of the notch 12, is preferably considerably higher than the bottom of the valley 11, so that water running down said valley will not run over 85 the lower edge 13, of the notch 12. The notch 12 is of substantially the same length as the desired lap in the shingles, so that if the lap of the shingles is to be considerable, the notch 12 will be made longer than 90 where the lap of the shingles is comparatively short. At the corner, diagonally opposite the notch 12, I form a notch 14 of substantially the same length as notch 12 and of a depth so that its top edge 15 can rest on 95 the edge 13 of another shingle in the roof.

In laying the shingles in a roof, they are preferably laid in horizontal rows, although they may be laid in vertical rows when so desired. In laying the shingles, I prefer- 100ably nail them, as at 16, in Fig. 1, to the strips 7. It will be noted that the edge 10 of one shingle extends over the edge 8 into the valley 11 of another shingle, so that water will be shed from the adjacent halves 105 of both of such shingles into said valley 11.

It will be noted that the edge 13 of one shingle, such for instance as indicated at A, in Fig. 1, is lower than the upper edge 17 of the edge portion 8 of shingle B, therefore, the edge 17 would catch any water which might splash up over edge 13 and 110

conduct such water downwardly through valley 11 of the shingle B. It will also be noted that when the shingle C is fitted in its place, its edge 13 will fit against edge 15 of shingle A, and that the edges 13 and 15 of shingles A and C will both lie on the upper end of the portion 8 of shingle D, thereby providing a substantially watertight joint. When another shingle is placed 10 above shingle A, the lower end of such shingle will overlap the edges 13 and 15 of shingles C and A respectively, further facilitating a substantially water-tight joint. It will be observed, however, that the lower 15 edge of each of the shingles in an upper horizontal row of shingles is substantially over the edge 18 of the notch 14 in a shingle below, but since the edge portion 8 under such edge 18 seals this joint, no water can 20 pass through the roof at edge 18, but will run down the valley of the shingle under such edge 18.

The shingles may be nailed so that all of the nails are hidden when so desired, 25 or if desired, the shingles may be nailed, as at 19, of shingle D in Fig. 1. The matter of nailing the shingles will depend upon the flexibility of the material in them and the amount of each shingle exposed to the 30 weather.

In Fig. 1 I have shown the strips 7 as being substantially triangular in cross section, but it will be understood that these strips may be formed of any other suitable 35 cross section.

In Fig. 4 I have shown a portion of a strip 7' which is of rectangular cross section.

While I have illustrated and described 40 the preferred form of my invention, I do not desire to be limited to the precise details set forth, but desire to avail myself of such variations and changes as come within the scope of the appended claims.

45 I claim:—

1. A roof comprising sheeting; spaced strips extending between the comb and eaves of the roof on the sheeting; and shingles covering the sheeting and strips, each shingle having a narrow portion at one longitudinal edge disposed upwardly and secured to one of said strips and the remaining portion of said shingle being in arched form and providing a valley between said 50 portions, the arch in each shingle being maintained therein by the upturned edge

portion thereof being secured to one of said strips and the other longitudinal edge of the shingle being disposed in the valley of an adjacent shingle. 60

2. A roof comprising sheeting; and overlapping shingles disposed on the sheeting in vertical and horizontal rows, each shingle having a narrow longitudinal edge portion inclined and the remainder of such shingle being arched in form with a valley between said portions, said narrow portion of each shingle being secured against movement on the sheeting and the longitudinal edge of such shingle opposite to said narrow portion being disposed in the valley of an adjacent shingle in the same horizontal row of shingles, there being two substantially rectangular notches in each shingle, said notches each being of a length corresponding to the length of the lap in the vertical lines of shingles and the combined widths of said notches being substantially equal to the width of the narrow edge portion, one of said notches being in the lower 70 end of said narrow edge portion and the other notch being in the diagonally opposite corner of said shingle therefrom. 75

3. A roof comprising sheeting; spaced strips extending between the comb and eaves 80 of the roof on the sheeting; and overlapping shingles covering the sheeting and strips disposed in horizontal and vertical rows, each shingle having a narrow portion at one longitudinal edge disposed 85 upwardly and secured to one of said strips, and the remaining portion of such shingle being in arched form and providing a valley between said portions, the other longitudinal edge of said shingle being disposed 90 in the valley of an adjacent shingle in the same horizontal row, there being two substantially rectangular notches in each shingle, said notches each being of a length corresponding to the length of the lap in the vertical lines of shingles and the combined 95 widths of said notches being substantially equal to the width of the narrow edge portion, one of said notches being in the lower end of said narrow edge portion and the other notch being in the diagonally opposite corner of said shingle therefrom. 100

In testimony whereof I have signed my name to this specification, on this 21st day of October, A. D. 1916.

EDWIN A. MASTICK.
